DESIGN FOR A DISPLAY BOX

Reginald A. Nagle, Rochester, N. Y.

Application August 6, 1940, Serial No. 94,265

Term of patent 14 years

To all whom it may concern:

Be it known that I, Reginald A. Nagle, a citizen of the United States, residing at Rochester, in the county of Monroe and State of New York, have invented a new, original, and ornamental Design for a Display Box, of which the following is a specification, reference being had to the accompanying drawing, forming part thereof.

The figure is a perspective view of a display box, showing my design.

I claim:

The ornamental design for a display box, substantially as shown.

REGINALD A. NAGLE.
